(57) **CLAIM**

The ornamental design for a lamp, as shown and described.

DESCRIPTION

FIG. 1 is a front perspective view of a lamp showing our new design;

FIG. 2 is a left side view thereof;

FIG. 3 is a right side view thereof;

FIG. 4 is a front elevational view thereof;

FIG. 5 is a rear elevational view thereof;

FIG. 6 is a top plan view thereof; and,

FIG. 7 is a bottom plan view thereof.

The perimeter of the claimed lamp fits within the ANSI A19 lamp profile. The claimed lamp can be used with a light emitting diode and could be used to replace an incandescent lamp.

The oblique lines on the canopy in FIGS. 1, 2, 3, 4 and 5 indicate that the canopy is either translucent or transparent. Portions of the lamp depicted in broken lines form no part of the claimed design. For example:

the broken line showing of the screw thread is for the purpose of illustrating the base of the lamp and forms no part of the claimed design; and

the broken line showing of the light engine and the light cone is for the purpose of illustrating structure that would be visible if the canopy were transparent and forms no part of the claimed design.
